Primary Examiner — Calvin E Vansant*Assistant Examiner* — Mark T. Philipp*(74) Attorney, Agent, or Firm* — Nitin Kaushik(57) **CLAIM**

The ornamental design for a air compressor, as shown and described.

DESCRIPTION

FIG. 1 is a front, left and top perspective view of a air compressor, showing our design.

FIG. 2 is a rear, right and bottom perspective view there of.

FIG. 3 is a front view there of;

FIG. 4 is a rear view there of;

FIG. 5 is a left side view there of;

FIG. 6 is a right side view there of;

FIG. 7 is a top view there of; and,

FIG. 8 is a bottom view there of.

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2;

and,

FIG. 12 is an enlarged view of portion 12 shown in FIG. 7.

The broken lines in the drawings illustrate the portions of the air compressor, which form no part of the claimed design.

1 Claim, 12 Drawing Sheets(56)
